ATTORNEY.

UNITED STATES PATENT OFFICE.

ANTHONY WILL, OF SYRACUSE, NEW YORK, ASSIGNOR TO THE WILL & BAUMER COMPANY, OF SYRACUSE, NEW YORK, A CORPORATION OF NEW YORK.

METHOD OF MAKING CANDLES.

1,294,008.

Specification of Letters Patent. Patented Feb. 11, 1919.

Application filed December 1, 1917. Serial No. 204,810.

To all whom it may concern:

Be it known that I, ANTHONY WILL, a citizen of the United States, and resident of Syracuse, in the county of Onondaga, in the 5 State of New York, have invented new and useful Improvements in Methods of Making Candles, of which the following, taken in connection with the accompanying drawings, is a full, clear, and exact description.

10 This invention relates to an improved method of making candles, the object of which is to form the moldable, inflammable material around the wick by axial compression and simultaneous feed of both material 15 and wick through a suitable die or mold so that the molding operation may be continuous and progressive for any length.

Another object is to regulate the temperature of the inflammable stock during its formation upon the wick.

Other objects and uses will be brought out in the following description.

In the drawings—

Figures 1 and 2 are, respectively, a top 25 plan and a longitudinal sectional view of a simple form of apparatus for carrying out the candle-making process, Fig. 2 being taken on line 2—2, Fig. 1 and showing the means for directing the wick through the 30 apparatus preparatory to receiving the inflammable envelop therefor.

Figs. 3, 4 and 5 are modified forms of dies 35 adapted to be used in the apparatus for shaping the candle to the desired cross sectional size and form.

The process, briefly stated, consists in passing a wick, as —a—, axially through a suitable die —1— and simultaneously forcing a moldable, inflammable material through the 40 same die and in the same direction so as to envelop the wick and bring the enveloping material to the desired cross sectional form and size in one and the same operation.

The apparatus shown for carrying out this 45 process comprises a tapered or conical shell —2— having means, as clamping screws —3—, at its smaller end for receiving and supporting the die —1— coaxial therewith, the larger end of the shell being provided 50 with a hopper —4— opening into the upper side thereof for supplying the moldable, inflammable material to the interior of the adjacent end of the shell.

A tubular shaft —5— extends lengthwise 55 of and is rotatable within the shell and is

provided with spiral blades —6— constituting with the shaft a screw for feeding the material from the hopper —4— to the small end of the shell and forcing it through the die —1—.

The shaft —5— is journaled in a bearing —7— on the large end of the shell —2— and is provided with a central opening —8— through which the wick —a— is drawn from a reel —9— so as to protrude into or 60 through the die —1—.

The end of the shaft —5— adjacent the large end of the shell —2— is provided with a pulley —10— which may be connected by a belt to any available source of power, not 70 shown, for rotating the shaft and its spiral blades —6— in the proper direction for feeding the material from the hopper —4— to the small end of the shell and thence through the die —1—.

The opposite end of the shaft and screw 75 preferably terminates short of the die —1— so as to leave an opening in the die around the wick of full size for receiving and shaping the material which is forced axially 80 therethrough by the screw.

During this operation, the material is compressed upon the protruding end of the wick —a— within the die and thereby draws the wick lengthwise through the opening 85 —8— in the shaft as the material is progressively fed through the die.

The material, such as tallow, wax or equivalent plastic substance, is preferably introduced from any source of supply into 90 the hopper —4— in a molten or fluid state so as to readily gravitate into the adjacent end of the shell —2— through which it is fed by the screw blades —6— into and through the die —1—, and in order that it 95 may be solidified sufficiently to take the form of the die while passing therethrough and to retain such form after its exit, a portion of the shell —2— between the hopper —4— and die is surrounded by a temperature-regulating chamber —11— having an inlet —12— and an outlet —13— for the entrance and exit of any temperature-regulating fluid, such for example as air, gas or liquid, of such temperature as to produce 105 the desired cooling or solidifying effect upon the material passing through the adjacent portion of the shell, the temperature of said air, gas or liquid being determined by a thermometer —14—.

The opening, as —1'— in the die may be of any desired cross sectional form, examples of which are shown in Figs. 3, 4 and 5 as round, square and corrugated, respectively.

What I claim is:

1. The herein described method of making candles consisting in passing a wick centrally through a tapered chamber and then continuously feeding an inflammable plastic material through said chamber in the direction of its taper whereby said material will be compressed at the small end of the chamber around and upon the wick with sufficient force to continuously draw the wick along with it in the same direction.
- 15 2. The herein described method of mak-

ing candles consisting in passing a wick centrally through a tapered chamber and then continuously feeding an inflammable plastic material through said chamber in the direction of its taper whereby said material will be compressed at the small end of the chamber around and upon the wick with sufficient force to continuously draw the wick along with it in the same direction and gradually solidifying the material as it approaches the delivery end of the chamber.

In witness whereof I have hereunto set my hand this 28th day of November, 1917. 30

ANTHONY WILL.
